United States Patent Office.

JEREMIAH SNELL, OF EVANS' MILLS, NEW YORK.

Letters Patent No. 91,783, dated June 22, 1869.

IMPROVEMENT IN GATES.

The Schedule referred to in these Letters Patent and making part of the same.

To all whom it may concern:

Be it known that I, JEREMIAH SNELL, of Evans' Mills, in the county of Jefferson, and State of New York, have invented a new and improved Gate; and I do hereby declare that the following is a full, clear, and exact description of the construction and operation of the same, reference being had to the accompanying drawings, making a part of this specification, in which—

Figure 1 is a side view.

Figure 2 is a transverse section of the fence, showing the gate open.

The object of this invention is to construct a simple and cheap farm-gate, which can be conveniently attached and operated, and which, when thrown open, will be entirely outside of the gate-posts, no part of it projecting into the roadway, so that by no possibility can a passing carriage come in contact with it.

In the drawings—

A is the post, against which the gate closes.

B is the post, which supports the gate.

C is a short, stout sill or base at the foot of post B, and parallel with the side of the roadway.

C' is an arm framed to the top of post B, over and parallel to sill C.

D is a spindle or upright shaft, bearing in the parts C C' and supporting the gate.

E is an inclined bar, fastened to shaft D at its lower end by a bolt, and connected to it at its upper end by a rod or brace, F, made adjustable by means of a screw-thread, f, and nut, a.

G is a roller attached to the side of shaft D.

G' is another, attached to the side of bar E, both rollers having a hub on their inner side, which holds them at a suitable distance from their supports, so that the flange of the sliding bar that works upon them, can run between them and the shaft or the bar E; and

I, the gate, consisting of the two parallel rails i i', connected by suitable upright pieces, and provided with intermediate rails, if preferred.

The under edge of the upper rail i is rebated or grooved along its centre, and rides upon the rollers, their edges working in the groove.

The upper edge of the lower rail slides under and in contact with the lower end of the inclined arm E, as shown at e, whereby the gate is held in place and prevented from tilting upon the rollers, or either of them, as it is slid back and forth.

H is a latch, by which the gate can be fastened when shut.

This improved gate is capable of two movements, either independent of or in combination with each other, namely, a swinging movement on the shaft D, and a sliding movement on the rollers G G', so that it can be readily and conveniently opened slightly, to admit a foot-passenger, or widely, to pass a loaded wagon.

When opened, as shown in fig. 2, it will be observed that the whole of the gate comes in rear of the post B, and entirely out of the way of injury from a carriage passing along the roadway, so that the carriage might strike the post, but could not come in contact with the gate itself.

The whole device is simple, convenient, not liable to get out of order, and can be erected at little expense.

Should it sag at any time, it can be set up by tightening up the nut a.

Having thus described my invention,

What I claim as new, and desire to secure by Letters Patent, is—

The grooved rail i of the gate, in combination with the rollers G G', the latter being arranged on a swinging frame D E F, substantially as and for the purposes set forth.

JEREMIAH SNELL.
